SAMUEL B. HOPKINS AND EDWARD H. ANDERSON, OF EASTON, ASSIGNEES
TO THEMSELVES AND J. M. SATTERFIELD, OF BALTIMORE, MARYLAND.

Letters Patent No. 77,612, dated May 5, 1868.

IMPROVEMENT IN VAPOR-BURNERS.

The Schedule referred to in these Letters Patent and making part of the same.

TO ALL WHOM IT MAY CONCERN:

Be it known that we, SAMUEL B. HOPKINS and EDWARD H. ANDERSON, of Easton, in the county of Talbot, and State of Maryland, have invented a new and improved Vapor-Burner; and we do hereby declare the following to be a full, clear, and exact description of the same, sufficient to enable those skilled in the art to which the invention appertains to fully understand and use it, reference being had to the accompanying drawings, forming part of this specification, in which—

Figure 1 is a top view.

Figure 2 is a vertical section through the line z of fig. 1.

Figure 3 is a vertical section through the line y of fig. 1.

This invention is an improvement upon the vapor-burner patented by us, April 3, 1860, and consists in using four holes instead of the two holes and slit of the former burner, and a transverse concave plate in addition to the concave plate shown in the former invention.

We construct or procure the single-tube fluid-lamps, of any known form, and insert the ordinary fluid-wick in the tube F of the lamp, in the usual manner, letting the wick project a little above the top of the tube. We then construct a short tube, D, just large enough to fit tightly over the tube F, and slide up and down upon it. To the top of the short tube D is attached a horizontal plate, B, curved upwards at its ends, and of the form shown clearly in fig. 1. Another plate extends across the centre of plate B, projecting upwards at its sides, opposite to the burner; or, in lieu of this second plate, the plate B may be provided with two ears, c c, extending outward and upward from its sides opposite to the burner, as shown in figs. 1, 2, and 3.

The burner A is of the ordinary shape, but instead of a slit, with two large holes at its extremities, is provided only with four holes—two small ones, a a, at the centre of the plate B, where it joins the burner, and two other small ones, a' a', on the sides of the burner, equidistant between the holes a a, but considerably higher. The jet that proceeds from these side holes a' a' impinges against the ears c c, and by heating them, serves more effectually to generate gas from the wick. The jets from the lower holes, a a, operate in the same manner, through the instrumentality of the plate B.

The great advantage of this improved form of vapor-burner over that hitherto used by us lies in the fact that its light cannot be extinguished by any sudden gust of wind striking it sideways. In the old burner, the flame, under such circumstances, was liable to be blown off of the plate, or to be blown away from the bent-up ends of the plate, so that they would become cooled, and the gas would cease to generate in the tube. This improved burner is not liable to that objection, for if the wind comes upon it in such a manner as to extinguish the jets from a a, the ears c c and the burner itself will protect the top jets, and prevent the light of one or both of them from being blown out. The flame, when blown sideways, will always envelope one of the ears c c, and the heat transmitted through that ear will keep up the temperature of the tube below, and prevent any interruption of the generating process within the tube. When the gust is over, the flame from the lighted top jet will relight the end jets, and the other top jet, if it shall have been extinguished.

At a suitable distance below the top of the tube D we attach a circular plate or button, E, by which to move the tube D up and down upon the wick-tube F. This button is made in the form shown in fig. 1, and is provided with a ring, e, of rubber, wood, or other suitable non-conducting substance, around its outer edge, to prevent it from burning the fingers when it is necessary to take hold of it.

The intensity of the light produced is regulated, as in the old lamp, by sliding the tube D up or down, thereby causing the heated burner to approach or recede from the wick, and thus increasing or diminishing the supply of gas.

Having thus described our invention, what we claim as new, and desire to secure by Letters Patent, is—
The burner above described, having the central cone A pierced with four holes, a a a' a', at the points

specified, when used in combination with a plate, B, bent up at the ends, and having ears, &c, projecting upward from its sides, substantially as and for the purpose described.

SAMUEL B. HOPKINS.
